(57) **CLAIM**

The ornamental design for a control console for desktop as shown and described.

DESCRIPTION

FIG. 1 is a front view of a control console for desktop showing our new design;

FIG. 2 is a rear view of the control console for desktop of FIG. 1;

FIG. 3 is a left side view of the control console for desktop of FIG. 1;

FIG. 4 is a right side view of the control console for desktop of FIG. 1;

FIG. 5 is a top view of the control console for desktop of FIG. 1;

FIG. 6 is a bottom view of the control console for desktop of FIG. 1;

FIG. 7 is a front, bottom perspective view of the control console for desktop shown in FIG. 1, with a center chamber in a raised, closed state; and,

FIG. 8 is a front, bottom perspective view of the control console for desktop shown in FIG. 1, with the center chamber in a recessed, open state.

The broken lines are for illustrative purposes only and form no part of the claimed design.

1 Claim, 8 Drawing Sheets
